US00D805366S

(12) **United States Design Patent** (10) **Patent No.:** **US D805,366 S**
Gassner (45) **Date of Patent:** **** Dec. 19, 2017**

(54) **HANDLE CLAMP FOR AN EXOTHERMIC WELDING MOLD**

(71) Applicant: **Hubbell Incorporated**, Shelton, CT (US)

(72) Inventor: **Gabriel J Gassner**, Tulsa, OK (US)

(73) Assignee: **Hubbell Incorporated**, Shelton, CT (US)

(**) Term: **15 Years**

(21) Appl. No.: **29/588,131**

(22) Filed: **Dec. 19, 2016**

(57) **CLAIM**

The ornamental design for a handle clamp for an exothermic welding mold, as shown and described.

DESCRIPTION

FIG. 1 is a perspective view of a handle clamp for an exothermic welding mold constructed in accordance with the present invention;

FIG. 2 is a top plan view thereof;

FIG. 3 is a left side elevation view thereof;

FIG. 4 is a bottom plan view thereof;

FIG. 5 is a right side elevation view thereof;

FIG. 6 is a front elevation view thereof; and,

FIG. 7 is a rear elevation view thereof.

The broken lines within the claimed design and the spaces therein are for environmental purposes only and form no part of the claimed design.

1 Claim, 5 Drawing Sheets
